CLAIM

The ornamental design for a children's camera, as shown and described.

DESCRIPTION

FIG. 1 is a front perspective view of a children's camera, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2;

FIG. 10 is a front perspective view thereof, shown with the children's camera in an open configuration; and,

FIG. 11 is a rear perspective view thereof.

The broken lines depict portions of the children's camera that form no part of the claimed design. The dot-dash-dot broken lines encircling an enlargement portion of the design forms no part of the claimed design.
